UNITED STATES PATENT OFFICE.

WALTER VON NESSEN, OF NEW YORK, N. Y., ASSIGNOR TO EFCOLITE CORPORATION, A CORPORATION OF NEW YORK.

DESIGN FOR A WALL BRACKET OR ANALOGOUS ARTICLE.

Application filed September 28, 1927. Serial No. 23,564. Term of patent 3½ years.

To all whom it may concern:

Be it known that I, WALTER VON NESSEN, a citizen of the German Republic, and a resident of New York, county of Bronx, and State of New York, have invented a new, original, and ornamental Design for a Wall Bracket or Analogous Article, of which the following is a specification, reference being had to the accompanying drawing, forming a part hereof.

The single figure in the drawing is a per-

spective view of the wall bracket or analogous article. The lining of the drawing is for the purpose of indicating shading, the design being more especially intended for porcelain wall brackets having smooth surfaces.

I claim:

The ornamental design for a wall bracket or analogous article substantially as shown and described.

WALTER VON NESSEN.
